UNITED STATES PATENT OFFICE.

BENJAMIN FRANK STONER, OF NEWARK, NEW JERSEY; ELLA V. STONER, ADMINISTRATRIX OF SAID BENJAMIN F. STONER, DECEASED.

AIRSHIP.

1,080,498.

Specification of Letters Patent.

Patented Dec. 2, 1913.

Application filed December 24, 1912. Serial No. 738,444.

To all whom it may concern:

Be it known that I, BENJAMIN F. STONER, a citizen of the United States, and resident of Newark, in the county of Essex and State of New Jersey, have invented certain new and useful Improvements in Airships, of which the following is a specification.

This invention relates to flying machines of the heavier-than-air class, and particularly to a machine combining the flying principles of the aeroplane and orthopter, the object of the invention being to provide a combination machine of this type in which the gliding and flapping surfaces act in a synchronized manner to give great supporting and flying efficiency.

A further object of the invention is to provide a machine which is inherently stable and otherwise capable of being safely operated, and which is adapted to be easily and sensitively controlled by the airman.

The invention consists of the features of construction, combination and arrangement of parts hereinafter fully described and claimed, reference being had to the accompanying drawings, in which:—

Figure 1 is a top plan view of a flying machine constructed in accordance with my invention. Fig. 2 is a side elevation of the machine. Fig. 3 is a front elevation thereof. Fig. 4 is a vertical longitudinal section. Fig. 5 is a sectional plan view on the line 5—5 of Fig. 4. Fig. 6 is a vertical transverse section on the line 6—6 of Fig. 4. Fig. 7 is an enlarged sectional view through one of the parachutes and its controlling means and showing the parachute spread for action.

In carrying my invention into practice, I provide a boat-shaped car 1, preferably of streamline form, and provided with a stabilizing tail piece 2. This car is supported by a main frame 3, which extends above and below the car and which supports front and rear launching and landing wheels 4, journaled in suitable bearing brackets supported by the framework. Within the car are arranged the aviator's seat 5, a pair of driving motors 6 and 7, and a steering shaft 8 provided with a hand wheel 9 disposed in proximity to the aviator's seat. The car may also contain the fuel carrying tanks, one or more passenger seats, and other parts of the equipment.

The main frame carries a gliding surface

in the nature of an aeroplane of substantially cruciform shape, and presenting head and tail portions 10 and 11 extending parallel with the line of flight and wings 12 and 13 projecting laterally in opposite directions at right angles to the line of flight, the machine as thus constructed being adapted when propelled through the air to sustain itself after the principle of machines of the gliding type.

Arranged beneath the lateral projecting wings 12 and 13 of the aeroplane surface are laterally projecting wings 14 and 15, of bird-like contour, each of which wings preferably consists of a framework having a covering of fabric or other suitable material 70 and including a longitudinal rod or shaft 16 reinforced from the frame proper by braces 17 and provided at its inner end with a ball or spherical member 18 journaled in the bearing socket 19. The two wings 14 75 and 15 are thus universally jointed to the framework to swing or flap in a vertical plane and to tilt or swing vertically to a certain degree on a transverse axis, so that in operation they may closely simulate the 80 action of the wings of flapping birds. It is found that this mode of operation of the wings 14 and 15 and their described relationship to the wings 12 and 13 of the cruciform aeroplane surface gives what may be 85 called a synchronized action in the way of a dual supporting effect, whereby a structure of great carrying and flying efficiency is produced.

The wings 14 and 15 carry eccentric straps 90 20, connected therewith by link rods 21, which eccentric straps coöperate with eccentrics 22 upon the opposite ends of a horizontal transversely extending shaft 23 journaled in the upper portion of the main 95 frame, whereby in the rotation of said shaft the wings will be simultaneously and alternately swung upward and downward on their universal joints and at the same time permitted to rock to a certain degree in a 100 fore and aft direction to give a pounding action on the air, whereby an aerodynamical supporting effect is obtained. The shaft 23 is driven by a sprocket chain 24 from the front motor 6, which chain passes around 105 sprocket wheels 25 and 26 on the shaft 23 and the shaft of the motor, respectively.

A forward driving or propelling action

is preferably secured by the use of a propeller 27 mounted in rear of the tail piece 2 upon a longitudinally extending shaft 28 driven by the rear motor 29, the action of 5 the propeller 27 driving the machine ahead at a proper speed for a guiding support through the medium of the aeroplane surface, while the action of the wings 14 and 15 at the same time gives a sustaining and 10 driving impulse.

The aeroplane surfaces 10 and 11 are provided with openings 30 in which are arranged front and rear horizontal rudders, elevators or altitude planes 31 and 32, which 15 are respectively mounted to tilt vertically on horizontal transverse shafts 33 and 34. These rudders are connected at their forward edges by links 35 to the upper arms of bell crank levers 36, the lower arms of which 20 are coupled by links 37 to controlling levers 38, one for each elevator or altitude plane, whereby said elevators or altitude planes may be simultaneously adjusted by simultaneous manipulation of the levers or independently adjusted by independent manipulation 25 of the levers to steer the machine vertically or balance it sensitively upon its transverse axis, the shape of the aeroplane surface and action of the flapping wings 30 giving inherent lateral stability without the use of lateral balancing means, although such may be employed if desired. Arranged beneath the tail portion of the car is a vertical rudder fin 39 hinged or pivoted at its 35 upper edge to swing laterally on a longitudinal axis, which rudder fin is coupled by connections 40 to the control shaft 8, whereby it may be adjusted laterally at an angle to the line of flight in either direction to 40 steer the machine laterally. This rudder fin may also be employed as a lateral balancing medium, and automatically operates to prevent skidding of the machine and to hold it against side draft in an intended line of 45 flight.

A stability vane 39' may be provided and located below the body of the car. This vane is supported by suitably guided rack bars 40' meshing with pinions 39^a on a shaft 50 40^b connected by gears 40^c with a vertical control shaft 40^d disposed in proximity to the aviator's seat and having an operating crank, whereby the vane may be raised and lowered.

The machine is preferably provided with 55 one or more parachutes in order to insure safety in the event of the collapse of a portion of the machine structure or the failure of the motive power, especially under conditions where a gliding landing cannot be 60 made. In the present instance the use of two parachutes is disclosed, each of which consists of an upwardly extending rod or staff 41 supporting a collapsible umbrella-shaped 65 parachute 42, said staffs being preferably disposed one in rear of the other and rein-

forced by a suitable connecting stay 43. The frame of each collapsible parachute includes stretchers 44 secured to a collar 45 fixed to the upper end of a sleeve 46 slidably mounted on the staff, which sleeve is also provided at its lower end with a collar 47 connected by links 48 with one arm of a bell crank lever 49, the opposite arm of which is coupled to a controlling lever 50. As shown the levers 38 and 50 are preferably mounted 70 on a common fulcrum 51, and each is provided with a spring actuated dog or latch 52 for engagement with a toothed segment 53, whereby it may be locked in adjusted position. 75

The sleeve 46 of each parachute is slidable 80 in a guide 54 and is adapted to be projected by the expansive action of a coil spring 55, which is normally held compressed when the parachute is collapsed and is adapted when released to project the sleeve upward and spread the parachute to open position. Chains or other flexible connections 56 connect the lower edges of the body of the parachute to the main frame or aeroplane surface, to limit the opening movement of said 85 parachute and to stay it against the pressure of the air when in action. It will be observed that the parachutes may be normally held collapsed, to reduce their resistance to 90 flight, and that they may be released at any time for automatic opening movement to support the machine in its descent and adapt it to land safely. 95

From the foregoing description, taken in 100 connection with the drawings, the construction and mode of use of my improved flying machine will be readily understood, and it will be seen that the invention provides a flying machine which, in an effective manner, combines the supporting principles of 105 the aeroplane and helicopter, enabling a reliable and efficient supporting action to be obtained, and that, in addition to the other safety factors mentioned, such use of the two 110 types of supporting surfaces disclosed gives greater security, as in the event of injury to the one the other will operate to sustain and maintain the machine in flight. 115

It will, of course, be understood that the 115 machine may be provided with a hydroplane surface of a suitable character for use on water as well as on land.

I claim:

1. A flying machine including a main frame, a boat shaped car carried thereby and having an attenuated tail portion provided with a transverse portion carrying a transverse tail piece, an aeroplane surface of substantially cruciform shape supported by the 120 frame, said surface presenting head and tail portions and transverse wing portions, flapping wings universally jointed to the frame and arranged beneath the transverse wing portions of the aeroplane surface, a propel- 125 130

ler shaft extending longitudinally above the tail piece of the car, a propeller carried by said shaft, a motor for driving the propeller shaft, a second motor, and mechanism actuated by said second motor for vertically swinging and rocking the flapping wings.

2. A flying machine comprising a boat shaped car having an attenuated tail portion with a transverse tail piece, a frame rising from the car, an aeroplane surface of substantially cruciform shape supported by the frame, said surface presenting head and tail portions and transverse wing portions flapping wings universally jointed to the frame and arranged beneath the transverse wing

portions of the aeroplane surface, a propeller shaft extending longitudinally above the tail piece of the car, a propeller carried by said shaft, a motor for operating the propeller shaft, a transverse transmission shaft 20 on the frame, eccentric mechanism actuated by said shaft for vertically swinging and rocking the flapping wings, and a second motor for driving said transmission shaft.

In testimony whereof I affix my signature 25 in presence of two witnesses.

BENJAMIN FRANK STONER.
